G. T. Griswold,

Tool Handle.

No 11,122. Patented June 20, 1854.

UNITED STATES PATENT OFFICE.

GEORGE W. GRISWOLD, OF CARBONDALE, PENNSYLVANIA.

TOOL-HANDLE.

Specification of Letters Patent No. 11,122, dated June 20, 1854.

To all whom it may concern:

Be it known that I, GEORGE W. GRISWOLD, of Carbondale, in the county of Luzerne and State of Pennsylvania, have invented 5 certain new and useful Improvements in Tool-Handles for Gimlets, Screw-Drivers, &c.; and I do hereby declare the following to be a full, clear, and exact description of the same, reference being had to the accompanying drawings, making a part thereof, in which—

Figure 1 represents a tool handle and gimlet therein and Fig. 2 represents the blade and accompaniments of a screw 15 driver, which may be used in the same handle.

I am fully aware that a spring pawl and ratch have been used in tool handles, so that the pawl will catch and hold while 20 turning in one direction, but will slip over the ratch when turned in the opposite direction. The application of such devices to tool handles enables the operator to run in a screw, or cause a gimlet to bore into the 25 wood, but the screw cannot be run back or the gimlet reversed so as to be drawn out by the same device. I am also aware that, a double acting pawl, has been used in a variety of machines. But these I do not claim 30 to have invented.

The nature of my invention consists in the so arranging of a double acting pawl on that part of a tool handle or holder, upon which the forefinger of the operator generally rests, and which pawl works into a star-shaped ratchet on the shank of the tool handle, as that, by the slight pressure of the forefinger, or the shifting of it from one side of the pawl to the other, will enable 40 him to run up, or back, a screw, by turning the handle in the ordinary continuous direction (from left to right).

To enable others skilled in the art to make and use my invention, I will proceed to describe the same with reference to the drawings.

A represents a tool handle which may be made of any convenient form for the hand, and B is the shank of the socket C—said 50 shank passing entirely through the handle as represented in red lines, and so arranged as to turn independent of the handle were it not for the double pawl D, which is so arranged

on the handle as that the forefinger of the operator may rest upon it, and govern the 55 direction of the rotation of the shank. As before stated the handle may be continuously turned from left to right (as shown by the arrow) and when the finger rests upon the side 1 of the pawl, a screw or 60 gimlet would be run into the wood, by turning said handle. Now continue to turn the handle in the same direction, but shift the point of the finger onto the side 2 of the pawl, and the screw or gimlet will be backed 65 out. The ratchet wheel E, is fast on the shank B, and may be just within the end of the handle to be out of the way, the teeth of the pawl passing through an opening in the handle to catch into said ratch. 70 The teeth of the ratch are “star shaped,” as they are termed—that is having the same inclination on both sides of the points of the teeth—the ordinary ratch having a greater inclination on one side of the tooth than on 75 the other.

F, in Fig. 2, represents the blade of a screw driver made to fit the same handle represented in Fig. 1.

G, is a tube surrounding the blade, and H, 80 a helical spring wound around the top of said blade—said spring (as represented in the drawing) being compressed to allow the blade F, to be placed in the nick of the screw, and when the tube is released it 85 passes over the head of the screw, and holds the blade to the screw head.

Having thus fully described the nature of my invention what I claim therein as new and desire to secure by Letters Patent, is— 90

So combining a double acting pawl, and star shaped ratchet with the stock and handle, of a screw-driver or gimlet, as that by pressing the thumb or finger on one arm of the pawl, and turning the handle the 95 screw may be driven into the wood, and by shifting the thumb or finger onto the other arm of the pawl, and continuing to turn the handle in the same direction, the screw or gimlet shall be drawn out of the wood, 100 substantially as described.

G. W. GRISWOLD.

Witnesses:

A. B. STOUGHTON,
THOMAS H. UPPERMANN.
